US0D1055185S

(12) **United States Design Patent** (10) **Patent No.:** **US D1,055,185 S**
(45) **Date of Patent:** **** Dec. 24, 2024**

(54) **WEIGHTLIFTING ATTACHMENT**

(71) Applicant: **Coulter Ventures, LLC.**, Columbus, OH (US)

(72) Inventor: **Martin Pritchett**, Columbus, OH (US)

(73) Assignee: **Coulter Ventures, LLC.**, Columbus, OH (US)

(**) Term: **15 Years**

(21) Appl. No.: **29/875,275**

(22) Filed: **May 2, 2023**

(51) LOC (14) Cl. **21-02**

(52) U.S. Cl.

USPC **D21/694**; D21/686

(58) **Field of Classification Search**

USPC D21/679, 680, 686, 694, 797; 482/41, 482/42, 123, 139, 135
CPC ... A63B 2210/50; A63B 3/00; A63B 23/1227; A63B 21/00047; A63B 21/4035; A63B 2225/093; A63B 2225/09; A63B 23/1218; A63B 1/00; A63B 21/068; A63B 23/1236

Primary Examiner — Ryan Harvey

(74) Attorney, Agent, or Firm — Banner & Witcoff, Ltd.

(57) **CLAIM**

The ornamental design for a weightlifting attachment as shown and described.

DESCRIPTION

FIG. 1 is a top, front, left perspective view of a weightlifting attachment showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom, front, right perspective view thereof.

The broken lines immediately adjacent to the shaded areas define the bounds of the claimed design and form no part thereof. The broken lines depicting the remainder of the weightlifting attachment form no part of the claimed design.

1 Claim, 8 Drawing Sheets
